Primary Examiner — Amy C Wierenga(74) *Attorney, Agent, or Firm* — Taylor English Duma LLP(57) **CLAIM**

The ornamental design for a pipe cap for drain pipe outlet, as shown and described.

DESCRIPTION

FIG. 1 is a front perspective view of a pipe cap for drain pipe outlet showing my new design;

FIG. 2 is a left side elevation view of the pipe end cap as shown in FIG. 1 showing my new design;

FIG. 3 is a right side elevation view of the pipe end cap as shown in FIG. 1 showing my new design;

FIG. 4 is a top plan view of the pipe end cap as shown in FIG. 1 showing my new design, the bottom plan view being a mirror image thereof;

FIG. 5 is a front elevation view of the pipe end cap as shown in FIG. 1 showing my new design; and,

FIG. 6 is a rear elevation view of the pipe end cap as shown in FIG. 1 showing my new design.

The broken lines shown in the drawings illustrate environmental structure and forms no part of the claimed design.
